Inventor:
Robert Malcom.
By-
J. MacLennan
Attorney.

Patented Nov. 22, 1927.

UNITED STATES PATENT OFFICE.

ROBERT MALCOM, OF CHICAGO, ILLINOIS.

GOOGLES.

Application filed November 1, 1920, Serial No. 421,142. Renewed February 21, 1927.

My invention has for its object the production of an improved form of eye protector or goggles, designed to be worn by workmen exposed to dust, dirt, cinders, flying particles, and the like, or by automobile drivers or others whose occupations require such protection for the eyes, and a respirator for the nose.

The particular object of my invention is to provide a novel construction of the eye cups or lens holding frames which can be assembled in a single operation wherein the body portion of said eye cups can consist of wire gauze, rubber, leather, or any other material suitable for the purpose, which is held in place by frictional engagement between two concentric rings, which rings are rigidly secured by a third member which also forms a seat for the lens without any extra parts or fastenings being employed for the purpose.

A further object of my invention is to provide means for securing the same to the head of the wearer whereby the eye protector may be easily adjusted to different sized heads, and also whereby the headband may be quickly and readily changed for renewal purposes, etc.

Further objects and advantages of this invention will be apparent to those skilled in the art and in the accompanying drawings I have illustrated what I now consider the preferred form of my invention, though it is obvious certain modifications may be made without departing from the spirit thereof, and in these drawings:

Fig. 1 is a side elevation of a pair of goggles embodying my invention,

Fig. 2 is a sectional view of one of the eye cups,

Fig. 3 is a side elevation of the holding rims,

Fig. 4 is an elevation of my invention illustrating its application to a respirator.

Referring to the drawings, 5 represents what I shall term the body portion of the eye cups, which can be formed of wire gauze, as shown in Figure 1, or of cloth, rubber, leather or any other suitable material.

6 and 7 are holding rings positioned concentrically with respect to each other, and receive between them the material forming the body portion either of the eye cups as shown in Figure 1, or of the respirator as shown in Figure 4.

The body portion 5 of the eye cups is held

in place through frictional engagement with the concentric rings 6 and 7.

Each of the rings 6 and 7 is provided with an inwardly extending flange 8, 9, respectively. The rings 6 and 7 are locked in positive engagement with each other by means of the circumferentially extending holding member 10 which forms a lens frame. The member 10 is provided with a circumferential shoulder 11, on which is seated the lowermost ring 9. The end of the tubular portion 12, which extends upwardly through the rings 6 and 7 is bent over to positively engage the flanges 8 and 9 as shown in Figure 2. This can be accomplished in a single operation, preferably by stamping or pressing without any extra parts or fastenings being employed for the purpose.

A lens 13 is seated against the shoulder 11 of the lens holding frame 10, as shown in Figure 2. The lens is held in place by the lens retaining ring 14, which is threaded to engage the lens retaining frame 10, as shown in Figure 2. The fore edge of this retaining ring 14 is bent inwardly and contacts with the outer edge of the lens 13 to hold it against the flange or shoulder 11. It will be obvious that this construction permits the lens to be quickly and easily removed if broken by unscrewing the retaining ring 14 for the purpose of exchanging same or for any other reason.

15 is a flexible connecting member between the eye cups forming a nose piece.

16 is a binding which may be secured around the edges of the eye cups if desired. In this instance I have shown a flexible binding which may be either rubber, felt, cloth or any other material suitable for the purpose. One desirable way of securing said binding in place is stitching the same through perforations in the eye cups, although it is obvious it may be done in any other method well known in the art.

The goggles are secured to the head of the wearer by means of the head band 17, which is preferably an elastic band, so fastened to the eye cups that it can be easily removed when desired.

Figure 4 illustrates the application of my invention to a respirator, wherein the body portion of the respirator, 18, usually formed of rubber is held by frictional engagement between two concentric rings of the form and construction illustrated by the parts 6 and 7 in Figure 2, which rings are held

in engagement with each other in the same manner as previously described.

In place of the lens 13 a perforated disk of any suitable material is seated upon the shoulder 11 formed on the inner ring 10 as heretofore described, and the disk will be held in place by the outer ring member 11 as described in Figure 2. This construction may be made large enough to fit over the nose and mouth of the wearer if desired.

I claim:

1. A device of the class described, comprising concentric rings having inwardly extending flanges at the forward edges, a body portion, one edge of which is held by frictional engagement between said rings, a threaded tubular member positioned within said rings and engaging the aforesaid flanges, a lens in said tubular member and a lens-retaining frame engaging said tubular member and holding the lens therein.

2. Goggles comprising concentric rings forming eyecups, a lens in each of the eye cups a body portion secured by frictional engagement between the concentric rings of each eye cup, a threaded tubular member securing said rings in positive engagement, a retaining ring engaging the aforesaid threaded member having the forward edge thereof bent inwardly to contact with the lens and hold it in place.

3. Goggles comprising a pair of eyecups, a movable connection between said eyecups,

forming a nosepiece, lens-holding rims, each consisting of two concentric rings, each of 35 said rings having an inwardly extending flange, a lens-holding member having a tubular portion extending through said rings and bent over in positive engagement with said flanges, thereby holding the body portion of the eye cup by frictional engagement between said rings and lenses removably mounted in said lens-holding members.

4. Goggles comprising a pair of eye cups, the body portion of said eye cups being 45 formed of flexible material lens-retaining rims comprising concentric rings, having inwardly extending flanges, the body portion of said eye cup being held by frictional engagement between said rings, a lens holding member having a circumferential shoulder contacting with said rings and forming a lens seat, said lens holding member having means formed integrally therewith for engaging said flanges, a lens seated in each of said lens holding members, retaining rings holding the lenses in place by screw threaded engagement with the ends of said lens holding members, a binding around the edges of the eye cups, and a head band secured to said eye cups substantially as described.

In testimony whereof I have signed this specification.

ROBERT MALCOM.
